(57) **CLAIM**

The ornamental design for a wireless repeater, as shown and described.

DESCRIPTION

FIG. 1 is a front and left side perspective view of a wireless repeater showing our new design with features illustrated in broken lines for illustrative purposes and thus not constituting a part of the claimed design;

FIG. 2 is a back and right perspective view of the wireless repeater of FIG. 1;

FIG. 3 is a left side elevational view of the wireless repeater of FIG. 1;

FIG. 4 is a right side elevational view of the wireless repeater of FIG. 1;

FIG. 5 is a front plan view of the wireless repeater of FIG. 1;

FIG. 6 is a back plan view of the wireless repeater of FIG. 1;

FIG. 7 is a bottom elevational view of the wireless repeater of FIG. 1; and,

FIG. 8 is a top elevational view of the wireless repeater of FIG. 1.

The dashed lines in the drawings are environmental and for illustrative purposes only and form no part of the claimed design. The dot-dash lines illustrate boundaries and form no part of the claimed design.
